Inventor

William G. Venard.

UNITED STATES PATENT OFFICE.

WILLIAM G. VENARD, OF SEATTLE, WASHINGTON.

BRACKET.

985,079.

Specification of Letters Patent. Patented Feb. 21, 1911.

Application filed May 2, 1910. Serial No. 559,026.

To all whom it may concern:

Be it known that I, WILLIAM G. VENARD, a citizen of the United States of America, and a resident of the city of Seattle, in the 5 county of King and State of Washington, have invented certain new and useful Improvements in Brackets, of which the following is a specification.

My invention relates to brackets, having 10 more particular reference to a device of this type particularly adapted for application to piles for facilitating the construction of scaffolds thereon, and has for its primary object the provision of a novel construction 15 of this type that can be readily and securely positioned on the piling.

A further object resides in the provision 20 of a construction of this type, the body portion of which can be adjusted to insure of its being maintained in proper position under adverse conditions.

With the above and other objects in view, to be referred to as my description progresses, my invention resides in the features 25 of construction, arrangements and combinations of parts hereinafter described and succinctly defined in my annexed claims.

Referring to the accompanying drawing, wherein like numerals of reference indicate 30 like parts throughout the several views: Figure 1 is a side elevation of my invention as in use, a portion thereof being broken away. Fig. 2 is a top plan thereof, a portion being broken away. Fig. 3 is an end 35 elevation, and Fig. 4 is a side elevation, with parts broken away, showing the device as applied to a leaning pile.

Referring to the drawing by numerals of reference, 1 indicates the body portion of 40 the bracket, and 2 and 3 bearing parts therefor, the former consisting of a block on which the said body portion 1 is fulcrumed, by a pivot 4, while the latter comprises a pair of spurs which are adapted to be embedded in the pile or other support, as 45 6, and thereby act conjointly with a suitable tie, as 5, in securing the device in position.

To insure of body portion 1 being properly positioned on leaning piles or poles, I 50 connect the same with bearing block 2 for relative bodily adjustment in inward and outward directions, such connection residing in adjustably supporting the pivot 4, the same having its opposite end portions adapted for reception in any of the seats of 55 the respective series of seats 7. These se-

ries of seats 7 which extend in an outward direction are formed in the cheeks 8 of block 2, the said cheeks extending from the end bearing wall 9, which is preferably curved 60 to conform to the contour of the pile (see Fig. 2) and projecting on respective sides of the upper portion of body 1.

Tie 5 is engaged with an eye 10 and keeper 11, provided on respective cheeks 65 of the bracket, to have its leads normally extend below pivot 4 thereof, whereby the body portion 1 is held under the desired tension and obviously prevented from accidental upward swinging. 70

In applying the bracket, pivot 4 is properly engaged with the desired seats of block 2, this depending on the position occupied by the pile (see Figs. 1 and 4), then with block 2 engaged with said pile tie 5 is 75 passed around the latter and made fast to keeper 11. Body 1 is now swung downwardly until bearings 3 engage the pile, as clearly shown.

In use, a number of piles are thus 80 equipped, and the desired scaffold completed by placing timbers thereon, as will be readily understood.

Having thus described my invention what I claim as new, and desire to secure by Letters Patent of the United States of America, 85 is:

1. A device of the type set forth comprising a bearing block provided with a series of seats extending in an outward direction, a 90 bracket provided with a pivot adapted for engagement in any of the seats of said series, and a securing means for said bracket.

2. A device of the type set forth comprising a bearing block provided with a series 95 of seats, a bracket having an adjustable pivotal connection with said block, and means carried by said bracket adapted to retain said pivotal connection in a predetermined position and secure the device to a support. 100

3. A device of the type set forth comprising a bearing block provided with a series of seats, a bracket provided with a pivot adapted to engage in said seats, and means carried by said bracket adapted to 105 retain the pivot in predetermined seats and secure the device to a support.

4. A device of the type set forth comprising a bearing block having spaced members each being provided with a series of 110 seats, a bracket adjustably fulcrumed on said block, and means carried by said

bracket for retaining the latter in its operative position.

5. A device of the type set forth comprising a bearing block having spaced members provided with a series of seats, a bracket fulcrumed in said spaced members, one portion of said bracket being adapted to bear against the support, and means carried by said bracket for retaining the latter in

an operative position on said bearing block 10 and the device to the support.

Signed at Seattle, Washington this 20th day of April, 1910.

WILLIAM G. VENARD.
